DRESSING DEVICE FOR GRINDING WHEELS

John Welsand, Jr., and Lloyd Leslie Lee, Detroit,
Mich., assignors to Eaton Manufacturing Company,
Cleveland, Ohio, a corporation of Ohio

Application June 5, 1942, Serial No. 445,868

12 Claims. (Cl. 125—11)

The present invention relates to grinding machines for grinding the inner member of a motor or pump comprising an outer internal gear-like member having a plurality of helical threads or teeth, the profile or form of which is preferably a circle, and an inner external gear-like member within the first member and having one less thread or tooth than the outer member, the form or profile of which is generated from the outer rotor and is such as to form with the outer member chambers which contract and expand upon relative rotation of the members.

More particularly the present invention relates to means for dressing a grinding wheel used for grinding the inner member of a device of the character referred to.

The invention resides in certain details of construction and combinations and arrangements of parts and further objects and advantages thereof will be apparent to those skilled in the art to which the invention relates from the following description of the preferred embodiment described with reference to the accompanying drawings forming a part of this specification in which similar reference characters designate corresponding parts and in which:

Fig. 1 is a transverse sectional view of the two gear-like members of the preferred embodiment of pump, the inner member of which it is desired to form-grind;

Fig. 2 is a diagrammatic view showing the principal movements of a dressing device for a grinding wheel, which dressing device embodies the present invention;

Fig. 3 is an end view of a dressing device for a grinding machine, which dressing device embodies the movements shown in Fig. 2;

Fig. 4 is a sectional view, with portions in elevation, approximately on the line 4—4 of Fig. 3;

Fig. 5 is an end view of the device shown in Fig. 4, looking from the right, with the grinding wheel omitted;

Fig. 6 is a section, with portions in elevation, approximately on the line 6—6 of Fig. 3;

Fig. 7 is a section on the line 7—7 of Fig. 4;

Fig. 8 is a section on the line 8—8 of Fig. 4;

Fig. 9 is an enlarged section approximately on the line 9—9 of Fig. 3; and

Fig. 10 is a section approximately on the line 10—10 of Fig. 9.

Referring to the drawings, Fig. 1 shows two members A and B of a pump on the order of the pumps shown in U. S. patent to Myron F. Hill, No. 1,862,563 issued August 28, 1928, disposed

one within the other. As illustrated outer member A has five internal teeth 10, the profile of which is an arc of a circle *i*, the center of which is at *j*, and the radius of which is *r*, referring to 5 the upper tooth as viewed in Fig. 1. The inner member B has four external helical teeth 11 conjugate to the teeth of the outer member A. As previously stated, the inner member or rotor usually has one less tooth than the outer member or rotor. Applying the principle that when 10 uniform rotary motion is transmitted by means similar to gear teeth, the normals to the profiles at all points of contact pass through the point of contact of their pitch circles, the form 15 of the inner rotor B is generated by the intersection of the profile circle *i* and a line *j*, *k*, see Fig. 2, connecting the center *j* of the profile circle *i* and the point of contact *k* of the respective pitch circles *l* and *m*.

According to the provisions of the present invention, a diamond or some similar dressing point for a grinding wheel is caused to travel the path traced by the intersection *n* of the profile curve *i* and a line *j*, *k* connecting the center *j* 20 of the profile circle *i* and the point of contact *k* between the outer rotor pitch circle *l* and the inner rotor pitch circle *m*, thus dressing the grinding wheel to the desired form. For mechanical reasons the pump is usually constructed 25 in such a manner that in operation the inner rotor B gyrates with reference to the outer rotor A but for present purposes it is assumed, for reasons which will be hereinafter more apparent, that the outer rotor A gyrates with reference to 30 the inner rotor B rotating in a counterclockwise direction around the stationary inner rotor B.

Fig. 2 shows the relative positions of the respective pitch circles, the profile circle *i*, and the centers thereof after the point of contact *k* between the outer rotor pitch circle and the inner rotor pitch circle has traveled 45°. Assuming that at the beginning the parts were in the position shown in Fig. 1, this angle represents the travel 45 of the line *k*, *o* connecting the center *o* of the outer rotor pitch circle *l* with the point of contact *k* between the pitch circles *l* and *m* about the center *p* of the inner rotor pitch circle *m*. The angle between the lines *j*, *o* and *k*, *o* represents the relative rotation of the outer rotor A about its center *o* which center traces the circle *q*. The reference character *s* indicates the center of the jackshaft gear pitch circle *t*, hereinafter more specifically referred to.

Referring to Fig. 4 of the drawings, the reference character C designates generally the frame

of the dressing device which is adapted to be attached in some suitable or convenient manner to the grinding machine. The grinding wheel to be dressed is designated generally by the reference character W. The dressing point D which, in the present instance is a diamond, is fixed in the projecting end of a diamond holder 12, the left-hand end of which, as viewed in Fig. 4, is adjustably secured by a clamp screw 13 in an angular hole 14 in a bracket 15. The bracket 15 is in turn fixed to the right-hand end of a shaft 16 rotatably supported by anti-friction bearings 17 and 18 in a housing assembly, designated generally by the reference character E. The center line j' of the shaft 16 corresponds with the center line j of the profile circle i , see Figs. 1 and 2.

The angular relationship of the hole 14 in the bracket 15 raises and lowers the diamond D relative to the center line j' of the shaft 16 as the diamond holder 12 is moved in or out of the hole 14. This adjustment provides means for setting the diamond D a distance below the center line j' corresponding to the radius of the profile circle i . The diamond holder 12 is adapted to be secured in any adjusted position within the bracket 15 by the clamp screw 13. A bar 20 shown in dot-dash lines in Fig. 4, the head 21 of which is made to the correct radius of the profile circle i , and is a half diameter, is preferably used for setting the diamond D in correct position. The shaft 16 has a coaxial aperture 22 therein adapted to receive the left-hand reduced end of the bar 20 and the half diameter line is kept in line with an imaginary line in the dressing device corresponding with the line j , k of Figs. 1 and 2 by a key 24 carried by the bar 20 and adapted to engage in a suitable keyway 25 in the shaft 16 and bracket 15.

The housing assembly E comprises a member 30 carried by a plate 31 keyed to the hub 32 of a gear 33, the pitch circle l' of which corresponds with the outer rotor pitch circle l . The gear 33 is supported by bearings 34 and 35 for rotation about a center line o' corresponding with the center of a shaft 36 keyed to a carrier 37 rotatably supported in the stationary frame or housing C by anti-friction bearings 38 and 39 for rotation about a center line p' corresponding with the center p , Figs. 1 and 2. Fixedly keyed to the right-hand end of the shaft 36, as viewed in Fig. 4, is a crank arm or eccentric 40 provided with a plunger 41 having a V-shaped end 42 which slidably engages in a V-shaped groove 43 in an arm 44 fixed to the left-hand end of the shaft 16. The plunger 41 is rotatably supported in the crank arm 40 and the axis of rotation k' thereof corresponds with the point k of Figs. 1 and 2 and corresponds with the point of contact between the pitch circle l' of the gear 33 extended corresponding with the outer rotor pitch diameter l and the pitch circle m' of a gear 45, hereinafter more specifically referred to, which pitch circle m' corresponds with the inner rotor pitch circle m . From the foregoing it will be apparent that the bottom of the V-shaped groove 43 in the arm 44 corresponds with the line jk of Figs. 1 and 2 and that the diamond point D is in line therewith. The gear 45 is formed integral with the right-hand end of a shaft 46 keyed to a plate 47 forming a part of the stationary housing C.

The carrier 37 is rotated about its axis of rotation p' by a gear 50, the teeth of which are continuously in mesh with gear teeth 51 formed about the periphery of the carrier. The assembly E, including the gear 33, is rotated about the

shaft 36 in timed relation to the rotation of the carrier 37 by two jackshaft gears 52 and 53 formed integral with a jackshaft 54 supported in the carrier 37 for rotation about a center line s' corresponding with the point s of Fig. 2. The pitch circles t' and t'' of the gears 52 and 53 coincide and correspond with the pitch circle t of Fig. 2. The gear 52 is continuously in mesh with the gear 45, the pitch circle m' of which corresponds with the inner rotor pitch circle m , and the gear 53 is continuously in mesh with the gear 33, the pitch circle l' of which corresponds with the outer rotor pitch circle l . In the embodiment of the invention shown, the jackshaft gears 52 and 53 are provided with conventional backlash eliminating mechanism 55 and 56. This mechanism per se forms no part of the present invention and will not be described in detail. Suffice it to say that any suitable backlash mechanism may be employed. As shown, the plate 31 is rotatably supported in the housing C adjacent to its circumference by anti-friction bearings 60 and 61 located on opposite sides of the plate. These bearings help to support the overhanging weight of the housing E and lessen the load to which the shaft 36 would be otherwise subjected.

Assuming that at the beginning of the dressing operation the parts are in the position shown in Figs. 3 and 4, the gear 50 and, in turn, the carrier 37 are rotated first in one direction to dress one-half of the wheel and then in the opposite direction to dress the other half of the wheel. To dress either half of the wheel it is only necessary to rotate the carrier 300°. As shown, when the carrier 37 is rotated in the counterclockwise direction, as viewed in Fig. 3, the left-hand half of the grinding wheel, as viewed in Fig. 8, is dressed, and, when the carrier 37 is rotated in the opposite direction, the right-hand half of the grinding wheel is dressed.

In the embodiment disclosed, the gear 50, through the medium of which the carrier 37 is oscillated, is keyed to a short shaft 62, see Fig. 6, rotatably supported in the housing C by anti-friction bearings 63 and 64 and is adapted to be oscillated in the required manner by a reciprocating type fluid pressure operated motor F comprising a piston 65 slidably supported in a cylinder 66 and connected by a piston rod 67 to a member 68 having rack teeth 69 formed integral therewith, which rack teeth are continuously in mesh with a gear 70 fixed to the shaft 62. The flow of fluid pressure to and from the fluid pressure motor may be accomplished in any convenient manner. It is preferably so constructed and connected with other operations of the grinding machine that the grinding wheel is automatically equally and uniformly periodically dressed.

In the embodiment of the invention shown, a uniform feed of the diamond point across the arcuate face of the grinding wheel is attained through the medium of a metering valve G which controls the supply or discharge of fluid from the fluid pressure motor F. As shown, the metering valve G is connected in the supply line but it is to be understood that it may be connected in the discharge line. The metering valve is connected to the fluid pressure motor F through a four-way reversing valve H, which reversing valve is preferably automatically controlled from some moving part of the machine so as to automatically effect a periodic dressing of the grinding wheel. The reversing valve H is of commercial construction and will not be described in detail.

Referring to Figs. 3, 9, and 10, the conduit 75 is connected to a source of fluid pressure and communicates with an orifice 76 in the metering valve G. The orifice 76 communicates with the interior of the valve G and an aperture 77 in the end of a slideable plunger 78. The flow of fluid from the orifice 76 to the aperture 77 and in turn to the conduit 80 leading to the reversing valve H is controlled or metered by the position of the plunger 78, the open end of which is closed or partially closed by the end of an adjustable pin 81 which provides means for adjusting the amount of fluid pressure which may be passed through the valve. The end of the plunger 78 opposite the aperture 77, that is the left-hand end, as viewed in Figs. 9 and 10, is provided with a roller 82 in engagement with a cam track 83 formed on the member 68. The contour of the cam track 83 is such as to compensate for the inherent characteristics of the movements employed in the dressing device which would normally cause the diamond point to travel across the arcuate face of the grinding wheel at a non-uniform rate. The reversing valve H is connected to the fluid pressure motor F by the conduits 85 and 86. The discharge conduit is designated by the reference character 87.

While the invention has been herein illustrated and described as embodied in a device for dressing a grinding wheel for grinding a particular member of a pump of specific construction, it is to be understood that the invention is not limited to a dressing device for dressing the specific grinding wheel shown but is applicable to the dressing of grinding wheels suitable for grinding rotors of pumps similar to the pump referred to herein but of different construction, and while the preferred embodiment of the invention has been described with considerable detail, it will be apparent that the invention is not limited to the particular construction shown which may be varied within the scope of this invention.

Having thus described our invention we claim:

1. A dressing device for a grinding wheel comprising: a housing; a carrier rotatably supported by said housing for rotation about an axis; a movable housing supported by said carrier for rotation about an axis parallel with but offset from the axis of rotation of said carrier; a shaft rotatably supported in said movable housing for rotation about an axis parallel with but offset from the axis of rotation of both said carrier and said movable housing; a crank on said carrier; means for operatively connecting said crank and said shaft, means operatively connecting said carrier and said housing for rotating said housing in timed relation to the rotation of said carrier; and a grinding wheel dressing tool operatively connected to said shaft.

2. A dressing device for a grinding wheel comprising: a stationary housing; a carrier rotatably supported by said housing for rotation about a fixed axis; a movable housing supported by said carrier for rotation about an axis parallel with but offset from the axis of rotation of said carrier; a shaft rotatably supported in said movable housing for rotation about an axis parallel with but offset from the axis of rotation of both said carrier and said movable housing proper; a crank on said carrier; means for operatively connecting said crank and said shaft; means comprising planetary gearing operatively connected to said carrier and said housing for rotating said housing in timed relation to the rotation of said carrier; means for rotating said carrier; and a grind-

ing wheel dressing tool operatively connected to said shaft.

3. A dressing device for a grinding wheel comprising: a first gear; a carrier assembly comprising a jackshaft having a second and third gear fixed thereto; means for rotatably supporting said carrier assembly coaxially with the center of the first-named gear; a member including a fourth gear; means for rotatably supporting said member by said carrier for rotation about an axis parallel with but offset from the axis of rotation of said carrier; means for rotatably supporting said jackshaft in said carrier assembly with its axis of rotation parallel with the axis of rotation of said carrier assembly and with said second and third gears in mesh with said first and fourth gears respectively; the pitch circles of said second and third gears when extended being coincident and the points of contact of the pitch circles of said second and third gears with said first and fourth gears respectively lying on a line parallel with the axis of rotation of the second, third, and fourth gears; a shaft rotatably supported in said movable housing for rotation about an axis parallel with but offset from the axes of rotation of both said carrier assembly and said movable housing; said carrier assembly comprising a crank the center of which is in line with the points of contact between the pitch circles of said first and second gears and the pitch circles of the third and fourth gears and offset from the axis of rotation of said shaft; means for operatively connecting said crank and said shaft; a grinding wheel dressing tool operatively carried by said shaft; and means for producing relatively rotation between said first gear and said carrier assembly.

4. A dressing device for a grinding wheel comprising: a stationary housing comprising a first gear; a carrier assembly comprising a jackshaft having a second and third gear fixed thereto; means for rotatably supporting said carrier assembly coaxially with the center of the first-named gear; a movable housing assembly including a fourth gear; means for rotatably supporting said movable housing assembly by said carrier for rotation about an axis parallel with but offset from the axis of rotation of said carrier; means for rotatably supporting said jackshaft in said carrier assembly with said second and third gears in mesh with said first and fourth gears respectively; the pitch circles of said second and third gears when extended being coincident and the points of contact of the pitch circles of said second and third gears with said first and fourth gears respectively lying on a line parallel with the axis of rotation of the second, third, and fourth gears; said movable housing assembly including a shaft rotatably supported therein for rotation about an axis parallel with but offset from the axis of rotation of said movable housing assembly proper; said carrier assembly including a crank the center of which is in line with the points of contact between the pitch circles of said first and second gears and the pitch circles of the third and fourth gears and offset from the axis of rotation of said shaft; means for operatively connecting said crank and said shaft; a wheel dressing tool operatively carried by said shaft; and means for rotating said carrier assembly.

5. In a dressing device for producing a profile including a reverse curve the combination of: a member; a tool holder; means for pivotally supporting said tool holder in said member for oscillation about an axis offset from the profile to be

produced and angularly disposed to the plane thereof; said tool holder having a tool extending transversely of the axis of oscillation of the tool holder; means for moving said member in a plurality of directions in a plane at right angles to the axis of oscillation of said tool holder; and means for oscillating said tool holder about its pivotal axis simultaneously with and in predetermined relation to the movement of said member whereby the longitudinal axis of the tool is always maintained substantially normal to the profile being produced at its point of contact therewith.

6. In a dressing device for a grinding wheel having a profile including a reverse curve the combination of: a member; a tool holder in said member; means for pivotally supporting said tool holder for oscillation about an axis offset radially outwardly from the grinding wheel and angularly disposed to its axis of rotation; said tool holder having a tool extending transversely of the axis of oscillation of the member; means for moving said member in a plurality of directions at right angles or normal to the axis of rotation of said tool holder; and means for oscillating said tool holder about its axis of oscillation simultaneously with and in predetermined relation to the movement of said member whereby the longitudinal axis of the tool is always maintained substantially normal to the profile of the grinding wheel at its place of contact therewith.

7. In a dressing device for a grinding wheel the combination of: a frame; a member; means for movably supporting said member in said frame for movement in a plurality of directions in one plane; a tool holder; means for pivotally supporting said tool holder in said member for oscillation about an axis perpendicular to the plane of movement of said member and offset from and angularly disposed to the axis of rotation of the grinding wheel; said tool holder having a tool extending radially of the axis of rotation thereof; means for moving said member in a plurality of directions in its plane of movement; and means for oscillating said tool holder about its pivotal axis simultaneously with and in such predetermined relation to the movement of said member that the longitudinal axis of the tool is always maintained substantially normal to the profile of the grinding wheel at its place of contact therewith.

8. In a dressing device for a grinding wheel the combination of a frame; an eccentric; means for rotatably supporting said eccentric; a member rotatably supported on said eccentric; a tool holder; means for pivotally supporting said tool holder in said member for oscillation about an axis perpendicular to the plane of movement of said member and offset from and angularly disposed to the axis of rotation of the grinding wheel; said tool holder having a tool extending transversely of the axis of rotation thereof; means for rotating said member and means for rotating said eccentric in timed relation to the rotation of said member whereby said member is moved in a plurality of directions in its plane of movement and the tool is caused to traverse a path including a reverse curve; and means for oscillating said tool holder about its pivotal axis in predetermined relation to the movement of said member whereby the longitudinal axis of the tool is always maintained substantially normal to the profile of the grinding wheel at its place of contact therewith.

9. In a dressing device for a grinding wheel the combination of a frame; a member rotatably

supported in said frame; an eccentric fixed to said member; a second member rotatably supported on said eccentric; a tool holder pivotally supported by said second member for oscillation about an axis parallel to but offset from the axis of rotation of said member and offset from and angularly disposed to the axis of rotation of the grinding wheel; said tool holder having a tool extending transversely of the axis of rotation thereof; means for rotating said member and means for rotating said second member in timed relation to the rotation of said member whereby said axis of said tool carrier is moved in a plurality of directions in a plane normal thereto and caused to traverse a path including a reverse curve; and means including a second eccentric connected to said member for oscillating said tool holder about its pivotal axis whereby the longitudinal axis of the tool is always maintained substantially normal to the profile of the grinding wheel at its place of contact therewith.

10. In a dressing device for a grinding wheel employed to form grind the inner rotor of a mechanism of the character described the outer rotor of which has arcuate lobes or teeth and the form of which inner rotor is generated from the outer rotor; the combination of: a frame; a first gear fixed to said frame and having a pitch circle corresponding with the pitch circle of the inner rotor; a carrier assembly; means for rotatively supporting said carrier assembly relative to said frame coaxially with the center of said first gear; an eccentric on said carrier assembly the center of which corresponds with the center of the pitch circle of the outer rotor; a member rotatively supported on said eccentric; a second gear fixed to said member and having a pitch circle corresponding with the pitch circle of said outer rotor and contacting the pitch circle of said first gear extended; a jack shaft; third and fourth gears fixed to said jack shaft; means for rotatively supporting said jack shaft in said carrier assembly so that the pitch circles of said third and fourth gears which are coincident contact said first and second gears respectively upon a line passing through the point of contact between the pitch circles of said first and second gears and the inner and outer rotors; a shaft rotatively supported in said member for rotation about an axis offset from but parallel with the axis of said first and second gears and corresponding with the center of the profile circle of the teeth or lobes of the outer rotor; a second eccentric on said carrier assembly, the center of which eccentric is in line with the points of contact between the pitch circles of said first and third, and said second and fourth gears and corresponds with the point of contact between the pitch circles of the inner and outer rotors; an arm on said shaft having a slot within which said second eccentric engages; a tool carried by said shaft, said tool having its longitudinal axis extending transversely of the axis of rotation of said shaft with the point of the tool extending towards said axis but offset therefrom an amount equal to the radius of the profile circle of the teeth or lobes of said outer rotor and corresponding with the intersection of the profile circle and a line connecting the center thereof and the point of contact of the pitch circles of the inner outer rotors; and means of producing a relative oscillation between said frame and said carrier assembly.

11. In a dressing device for a grinding wheel employed to form grind the inner rotor of a mech-

anism of the character described the outer rotor of which has arcuate lobes or teeth and the form of which inner rotor is generated from the outer rotor, the combination of: a frame; a first gear fixed to said frame and having a pitch circle corresponding with the pitch circle of the inner rotor; a carrier assembly; means for rotatively supporting said carrier assembly relative to said frame coaxially with the center of said first gear; an eccentric on said carrier assembly the center of which corresponds with the center of the pitch circle of the outer rotor; a member rotatively supported on said eccentric; a second gear fixed to said member and having a pitch circle corresponding with the pitch circle of said outer rotor and contacting the pitch circle of said first gear extended; a jack shaft; third and fourth gears fixed to said jack shaft; means for rotatively supporting said jack shaft in said carrier assembly so that the pitch circles of said third and fourth gears which are coincident contact said first and second gears respectively upon a line passing through the point of contact between the pitch circles of said first and second gears and the inner and outer rotors; a shaft rotatively supported in said member for rotation about an axis offset from but parallel with the axis of said first and second gears and corresponding with the center of the profile circle of the teeth or lobes of the outer rotor; a second eccentric on said carrier assembly, the center of which eccentric is in line with the points of contact between the pitch circles of said first and third, and said second and fourth gears and corresponds with the point of contact between the pitch circles of the inner and outer rotors, an arm on said shaft having a slot within which said second eccentric engages; a tool carried by said shaft, said tool having its longitudinal axis extending transversely of the axis of rotation of said shaft with the point of said tool extending towards said axis but offset therefrom an amount equal to the radius of the profile circle of the teeth or lobes of said outer rotor and corresponding with the intersection of the profile circle and a line connecting the center thereof and the point of contact of the pitch circles of said first and second gears and the inner and outer rotors; and means of producing a relative oscillation between said frame and said carrier assembly at a variable speed such that the point of the tool traverses the profile of the grinding wheel at substantially uniform speed.

12. In a dressing device for a grinding wheel employed to form grind the inner rotor of a mechanism of the character described the outer rotor of which has arcuate lobes or teeth and the form of which inner rotor is generated from the outer

5 rotor, the combination of: a frame; a first gear fixed to said frame and having a pitch circle corresponding with the pitch circle of the inner rotor; a carrier assembly; means for rotatively supporting said carrier assembly relative to said frame coaxially with the center of said first gear; an eccentric on said carrier assembly the center of which corresponds with the center of the pitch circle of the outer rotor; a member rotatively supported on said eccentric; a second gear fixed to said member and having a pitch circle corresponding with the pitch circle of said outer rotor and contacting the pitch circle of said first gear extended; a jack shaft; third and fourth gears fixed to said jack shaft; means for rotatively supporting said jack shaft in said carrier assembly so that the pitch circles of said third and fourth gears which are coincident contact said first and second gears respectively upon a line passing through the point of contact between the pitch circles of said first and second gears and the inner and outer rotors; a shaft rotatively supported in said member for rotation about an axis offset from but parallel with the axis of said first and second gears and corresponding with the center of the profile circle of the teeth or lobes of the outer rotor; a second eccentric on said carrier assembly, the center of which eccentric is in line with the points of contact between the pitch circles of said first and third, and said second and fourth gears and corresponds with the point of contact between the pitch circles of the inner and outer rotors, an arm on said shaft having a slot within which said second eccentric engages; a second member fixed to said shaft, said second member having an aperture therein offset from and angularly disposed with respect to the axis of said shaft; a tool holder adjustably secured in said aperture in said second member; a tool carried by said tool holder, said tool having its longitudinal axis extending transversely of the axis of rotation of said shaft with the point of the tool extending towards said axis but offset therefrom an amount equal to the radius of the profile circle of the teeth or lobes of said outer rotor and corresponding with the intersection of the profile circle and a line connecting the center thereof and the point of contact of the pitch circles of said first and second gears and the inner and outer rotors; and means of producing a relative oscillation between said frame and said carrier assembly at a variable speed such that the point of the tool traverses the profile of the grinding wheel at substantially uniform speed.
